United States Patent

Des. 239,282
Patented Mar. 23, 1976

239,282

REVOLVER

Ralph C. Kennedy, South Windsor, and Richard L. Baker, Wallingford, Conn., assignors to The Leisure Group, Inc.

Filed Aug. 12, 1974, Ser. No. 496,756

Term of patent 14 years

Int. Cl. D22—01

U.S. Cl. D22—1

FIG. 1

FIG. 2

FIG. 3

FIG. 4

FIG. 5

FIG. 6

FIG. 1 is an enlarged side elevational view of a revolver showing our new design;

FIG. 2 is a reduced-scale view of the opposite side of the revolver shown in FIG. 1; and

FIGS. 3, 4, 5 and 6 are top plan, bottom plan, front and rear views, respectively, of the same on the same scale as FIG. 2.

We claim:

The ornamental design for a revolver, substantially as shown.
